SAFETY HOIST

Carroll C. Figge, Batavia, Ill.

Application July 11, 1957, Serial No. 671,270

13 Claims. (Cl. 214—628)

This invention relates in general to a hoist and is more particularly described as a safety automatic dumping hoist particularly for use in building operations and by roofers although it may have a more general use wherever applicable.

In building operations for roofing, and the like, it is current practice to provide a projecting beam as a support for a pulley and to raise materials in a bucket or other container at the end of a rope to the desired height. At an upper level or on top of a roof, a workman may reach out and engage the raised material pulling it inwardly through a window or at the top of a roof. This is a dangerous practice not only for the workmen at the upper level since the material may be hot and in pulling it inwardly, the material may be spilled, making it hazardous at the upper level and also for other workmen at a lower level or on the ground who may be filling the buckets or other receptacles and operating the hoist.

The present invention overcomes these objections by providing a platform carried by the projecting support at the upper level having a pivoted member engaged by the bucket or a load which swings the platform outwardly below the bucket or load to receive the contents of the bucket or receptacle which is automatically discharged upon the platform in an inclined position which directs the material inwardly through a window or inwardly of the edge of a roof.

With this construction, it is not necessary for a workman to reach out for the load, to pull it inwardly, or to attempt to discharge or overturn a bucket, but the material is automatically discharged upon the inclined platform and is guided to the interior of the building or to a wheelbarrow or other load carrying means.

In connecting, hoisting, and disconnecting a bucket or other load carrying receptacle, an open hook on the end of a hoisting rope is usually engaged with a ring or loop at the top of the bucket, but is hoisting hot materials for roofing and other loose materials which are likely to spill or fall, it is a dangerous practice since the materials may injure the workmen at the upper levels as well as upon the ground.

In order to more safely connect a load receptacle, a safety hook construction is employed in which the handle, bail or support for the load carrying receptacle is connected to the hoisting rope by a safety hook which requires that the bail or handle be first inserted between parallel portions of the hook and then relatively raised and rotated to engage opposite hook portions and then dropped to the bottoms of the hook portions to prevent their accidental disengagement.

An important object of the invention is to provide a platform normally out of the path of movement of a hoist receptacle which is projected below the receptacle after it passes the platform so that the receptacle may discharge its contents upon the projected platform without requiring that the receptacle be grasped and pulled in by a workman.

A further object of the invention is to provide a plat-

2

form which is actuated by an overhanging lever having a portion in the path of a hoist to swing the platform outwardly below a load after the load has passed the platform and to incline the platform inwardly from the outer projected portion thereof.

A still further object of the invention is to provide an improved safety connection for a hoist which comprises a hook requiring that the bucket or other load containing means be supported by a pair of oppositely turned hooks which prevent disengagement of a bail in either direction of turning and also in a relatively raised position.

Still a further object of the invention is to provide a pivotally supported platform in connection with an operating lever, one end of which projects in the path of a hoist, in which the platform is bodily projected from an inner position free from engagement with a hoisted load into an inclined position below the load to automatically direct the contents of the hoisting bucket upon the inclined and projected platform when the upper projecting end of the operating lever is engaged.

A still further object of the invention is to provide a hoist with a safety double locking hook which may be manually engaged and disengaged by relatively raised, rotating and lowering the supporting bail of a bucket in order to effect double engagement or disengagement of one from the other.

Other objects of the invention will appear in the specification and are more apparent from the accompanying drawings in which,

Fig. 1 is a broken elevation of a safety hoist in accordance with this invention as applied to a portion of a roof of a building;

Fig. 2 is a perspective view of a safety double hook as connected in Fig. 1, compressed for separating the hooks;

Fig. 3 is an end elevation of the hook as taken in a plane of the line 3—3 of Fig. 2; and

Fig. 4 is a perspective of a safety double hook which may be of heavier material with the hooks spread apart, and requiring no separation of the hooks.

This invention provides a platform normally positioned within the walls of a building, but having a supporting part which extends into the path of a load outside of the building and above the platform so that when the projecting portion of the support is engaged by the load, it will swing the platform outwardly below the load in an inclined position, to direct the contents of a bucket inwardly of the walls or roof of a building so that a workman receiving the load is not required to lean outwardly from the building to direct the load inwardly, to cause the discharge of a load from a bucket, thereby freeing him and other workmen from any danger from heated or falling material and from accidental loss or spillage of the material itself.

Referring now more particularly to the drawings, a hoist in accordance with this invention is illustrated in connection with the side of a building 10 and a roof parapet 12 therefor by providing spaced vertical supports 14 (only one shown) in the nature of a scaffold having a connecting footpiece 16 at the bottom, a horizontal beam or beams 18 at the top, and an angular brace 20 or braces extending from the beam 18 to the support 14.

At the rear or inner end of the beam 18, there may be a stabilizing structure comprising a vertical support 22 extending to the floor or roof with an angular brace 24 from the inner end of the beam to the lower portion of the vertical support and at the base of the support is a footing 26 to which sandbags or other weights may be applied in supporting the outer end of the beam if necessary.

At the outer end of the beam (or between adjacent beams) 18 are pulleys 28 and 30 over which a hoisting rope or cable 32 is passed to support a load or bucket

and to provide means for raising or lowering the bucket close to the side of a building.

At the inner sides of adjacent vertical posts or supports 14, a platform 34 is mounted for movement into and out of the wall of the building, and relatively inwardly or outwardly with respect to the vertical supports 14. This platform is of sufficient width to receive a bucket 36 supported by the cable 32 between the side edges thereof. Near the front or projecting end of the platform, it is adjustably suspended as by means of a chain 38 at each side thereof, the upper end of the chain being supported by means of a hook or pin 40 projecting inwardly from one of the post supports 14 and the lower end of the chain being connected to a pin or projection 42 at corresponding spaced locations along each side so that when both chains are connected to opposite posts 14, the platform will be suspended by the chains and will swing freely between the supports.

Near the rear end of the platform 34, it is supported at each side by a rigid lever 44 each mounted intermediate its ends at the inner side of one of the supports 14 upon a pivot 46, the lower end being connected by a pivot 48 with the corresponding edge of the platform 38. At the other end of the lever is a projecting end 50 which extends beyond the side support 14 to which it is connected and between the corresponding ends of these levers 44 may be a connecting yoke 52 through which the cable 32 passes somewhat freely but which is adapted to engage the top or upper supporting portions of a load bucket 36 or other receptacle.

When the bucket is raised, the yoke 52 or the projecting ends of the levers are engaged by the bucket which causes the projecting ends of the levers to move upwardly, swinging the inner end of the platform 34 outwardly upon the side chains 38. These chains being connected to pins 40 below the pivots 46 of the levers and on a smaller radius, causes the outer end of the platform to be swung upwardly when it is projected outwardly by the levers 44. This locates the outer end of the platform below a bucket 36 or other receptacle at such an inclination that material discharged therefrom will fall directly upon the platform and downwardly thereon into a wheelbarrow 54 or some other receptacle at the lower end of the partition within the wall or parapet 12 of the building.

The inclination of the platform, both before and after its projection may be varied to some extent by relatively shortening or lengthening the chain 38 and also by providing a number of supporting pins 40 at different elevations on the sides of the post supports 14 to correspondingly vary the relative radius of curvature of the support of the outer end of the platform. Likewise the effective length of the levers 44 connected to the inner end of the platform may be changed by connecting the pivots 48 in one of a number of pivot holes 56 near the lower end of each lever.

Any suitable receptacle for automatically discharging a load therefrom may be employed in connection with the hoisting cable and the contact means or yoke 52 connecting the ends of the lever 44 which is represented in the bucket 36 which has opposite shell portions 58 connected by a cross pivot 60 at the top to which the cable 32 or an extension 62 thereof is connected and each of the shells has an operating lever 64 opposite the pivot with one arm connected to the shell and the other arm extending within a ring 66 through which the cable 32 or its extension 62 may project. The cable passes freely through the yoke 52 connecting the ends 50 of the levers 44, but the ring 66 engages the under side of the yoke so that as the bucket is raised against the pressure of the ends 50 of the levers 44, the ends of the operating levers 64 will be pressed downwardly toward the pivot 60 connecting the shells of the bucket which will therefore be forced open at the bottom when stopped at the completion of its raising movement, in a well known manner, to discharge the contents of the bucket upon the platform

34 which has been moved in the meantime by such engagement with the upper ends of the rigid mounting levers 44 which swing upon the pivots 46.

In the reverse movement of the bucket, after the load has been discharged, the first downward movement of the bucket releases the levers 44 at their upper ends which thereupon swing downwardly drawing the platform inwardly and closing the opposite shells of the dumping bucket. Other types of discharging receptacles may be used for discharging liquids or fluid materials by engaging a valve member upon contact with the yoke 52 which opens the valve in the bottom of the receptacle. The discharging receptacle forms no particular part of the present invention.

In connecting the cable 32 to a bucket or other discharging receptacle, an opposite double looped safety link as shown in Figs. 2, 3 and 4 is provided, one being of lighter metal which may be manually deflected as shown in Figs. 2 and 3, and the other being of heavier metal which is not easily flexed by hand.

In the hook shown by Figs. 2 and 3, a double loop 70 is formed intermediate the ends of a piece of stiff metal bar stock from which outwardly spaced parallel portions extend which are at right angles to hooked portions 74 at the extremities normally held in close together parallel relation and the extremity 76 of each hook portion being bent oppositely and substantially over the opposite hooked portions 74. The double loop at the upper end forms a light spring action which tends to hold the parallel portions 72 apart and to hold the hooked portions 74 together in close relation with the extremities 76 extending over and partially overlapping the opposite hooked portion.

With this construction, a bail, handle, or cross pivot 60 can only be engaged or disengaged from the double hooked portions 74 by first separating these portions, pressing inwardly on the parallel portions 72, inserting a cross bar (or the link of a cable extension 62) between the hooked extremities raising the bar or link above the bent and outwardly turned extremities 74 giving the safety hook a relative quarter turn to free them from the extremities 76 and then relatively dropping the bail, cross pivot or eye of the cable extension 62 downwardly in engagement with both of the hooked portions 74, and reversing these operations for disengaging the safety hook from a bail member to which it is connected. The double loops 70 at the upper end of the safety hook may have a fixed or permanent connection as indicated in Fig. 2 with a cable 32.

The safety hook shown in Fig. 4 is made of heavier bar stock bent to the desired shape but relatively stiff so that it is not easily bent or manipulated by hand. In this safety hook, a double hook 80 is made intermediate the ends of a piece of bar of stock and portions 82 extending therefrom are given a half twist between the double loop and the hooked ends 84 so that the latter are permanently spaced apart substantially the width or slightly more than a bail or bar 86 which is to be connected to the hooked ends.

Each hooked end has a bent extremity 88 turned downwardly and outwardly so that a space slightly more than the width of a bar 86 is opened between the bent extremity 88 and the hooked end 84 of one of the hooked extremities.

With this construction, a bar 86 is first inserted between the two hooked ends 84 entering at the position 1 as shown at Fig. 4, and then moved upwardly parallel with the hooked ends 84 to a position above the bent extremities 88 to the position 2. The bar is then turned at an angle of slightly more than 90° to position 3 overlying and beyond the bent extremities 88 whereupon the bar will clear the extremities and may be moved downwardly to position 4 and seated in the loops of the hooked ends 84 which is the final position in this safety hook and from which the bar cannot be disengaged except

by reversing the operation just described. The advantage of this construction is that after a bar or bail as 86 is once seated in the double hooked ends 84, it cannot be disengaged by accident or inadvertence and even if turned, raised or twisted, the downwardly bent extremities 88 will substantially prevent any disengagement of the safety hook without manual manipulation thereof.

The connection of a safety hook between a bucket 36 or other receptacle and the lifting cable 32 prevents accidental disengagement of the receptacle even though there is a contact engagement between the receptacle and the supporting levers 44 to cause the operation of the platform 34. No bumping, turning or relative lifting movement is sufficient to accidentally disengage the double loop of the safety hook from its connection with the receptacle. This contributes materially to the safe operation of a hoist of this kind, it prevents accidental disengagement of a bucket or receptacle and provides means for quickly engaging different buckets or receptacles from the same hoisting cable when desired.

In actual erection of the supporting structure on a roof or in the floor of a building, the supporting and bracing parts are preferably made of wood or light iron, connected together at the joints by bolts which are easily attached and disengaged but the special relation of the supporting parts and such connection constitutes no material portion of the present invention.

While a complete safety hook hoisting apparatus for automatic discharge of materials has been thus described in some detail, it should be regarded by way of example and illustration rather than as a limitation or restriction of the invention as various changes in the construction, combination and arrangement of the parts may be made without departing from the spirit and scope of the invention.

I claim:

1. In a hoist for buildings, and the like, a beam extending at one end to project beyond the side of a building, means for supporting the projecting end of the beam in overhanging relation to a floor or roof level of the building, pulley means carried by the overhanging portion of the beam outside of the building, a load receptacle and cable means connected thereto and extending over the pulley means for raising material in said receptacle with respect to the beam, a platform and means for mounting it in free swinging relation with respect to said supporting means to swing into and out of the path of the load receptacle and including a lever pivoted intermediate its ends above the platform and engaged by the upper end of the load receptacle at the completion of its raising movement to bodily move the platform and swing the outer end of the platform upwardly into the path of and below the load receptacle to receive material discharged therefrom.

2. In a hoist in accordance with claim 1, a flexible and extensible support for each side of the front end of the platform which may be varied in length to swing the front end of the platform upwardly and below the load receptacle at different angles.

3. In a hoist in accordance with claim 2, said flexible and extensible means comprising a chain which is connected at its upper end to said supporting means and is connected at the lower end of the platform, the effective length of the chain being varied to swing the platform about different axes.

4. In a hoist in accordance with claim 1, the lever means having an arm in the path of the receptacle and engaged thereby and the opposite end of the lever having a variable pivot connection with the rear end of the platform to change the inclination of the platform when it is at rest and when it is projected outwardly below the receptacle.

5. In a hoist in accordance with claim 2, the said flexible and extensible means being connected to the front end of the platform and the lever means being connected to the rear end of the platform so that the platform is

normally located out of the path of the receptacle, but is mounted by said flexible and extensible means upon a radius which is less than the radius of the lever means so that the front end of the platform will tilt upwardly below the load receptacle at a greater angle than in its at rest position within the side of a building for receiving and directing material discharged from the load receptacle downwardly on the platform within the building.

5 6. In a hoist in accordance with claim 1, for buildings and the like, the load receptacle having its cable supporting means connected at the top thereof for engaging one arm of the lever and having a bottom discharging means which is operated to open the discharge when the cable supporting means at the top engages the projecting end of the lever below the overhanging portion of the beam in the raising movement of the receptacle.

10 7. In a hoist for buildings in accordance with claim 6, the load receptacle having a support at the top and opening at the bottom to discharge material and a releasable connection between the top support and the supporting cable which is movable past the projecting end of the lever means without actuating it, the lever being engaged and actuated by the load receptacle support.

15 8. In a hoist for buildings and the like, a beam extending at one end to project beyond the side of a building in overhanging relation from a floor or roof level of the building, pulley means carried by the overhanging portion of the beam outside of the building, a load receptacle and cable means connected at the top thereof and extending over the pulley means for raising material in said receptacle with respect to the beam, a platform and means for mounting it in free swinging relation with respect to the supporting means to swing into and out of the path of the load receptacle and including a lever pivoted intermediate its ends above the platform and engaged by the upper end of the load receptacle in its raising movement to bodily move the platform and swing

20 40 the outer end of the platform upwardly into the path of and below the load receptacle to receive material discharged therefrom, the load receptacle having bottom discharging means operated to open the discharge when the cable means at the top engages the projecting end of the lever at the completion of the raising movement of the receptacle, the load receptacle bottom discharge means having opposite shell portions pivotally connected to the receptacle to swing open at the bottom, a lever having one arm attached to each shell and the other arm of each lever engaging within a ring through which the cable extends, the ring being of a diameter to engage the projecting end of the beam, the said beam having an opening through which the cable extends but through which the said ring will not pass so that the ring engages the projecting end of the beam to open the shells when the load receptacle is raised by its cable means to make contact with the projecting end of the beam, and a double safety link connecting the bucket and the supporting cable which extends freely through said ring and also is free from engagement with the projecting end of the beam.

25 45 55 60 9. A hoist in accordance with claim 8, in which the said connecting link has a closed double loop at one end with a fixed engagement to one of the parts which it connects and a pair of opposite hooks at the other end spaced apart to receive a supporting member of the other part which it connects, the hooks being rotated relatively to the supporting member to oppositely engage both of them and the extremities of the hooks being bent oppositely over the opening of the hooks to prevent disconnection to the other part to which it is connected.

65 70 10. A safety link in accordance with claim 9 comprising a bar permanently bent intermediate its ends to form a double spring loop and the ends of the bar bent oppositely to form overhanging hooked extremities with intermediate portions between the hooks and the loops

which are substantially parallel, the extremity of each bar near the hook extending laterally from the hook and providing means for engaging a bail or a support of the other part which it connects to prevent accidental disengagement from the double hooks.

11. A safety link structure in accordance with claim 10 in which the intermediate portions of the bar between the double spring loop at one end and the hook portions at the other ends are given a twist to hold the said intermediate portions in parallel relation.

12. A safety link structure in accordance with claim 11, in which the said twist places the intermediate portions at right angles to the hook portions so that the parallel portions may be pressed together separating the hooks for the insertion of a connecting part between the hooks.

13. A safety double hook structure in accordance with claim 12 in which the hook is made of relatively stiff bar material so that the said intermediate portions near the end of the hook are not manually compressible and the

extremities of the hooks are bent reversely and the hooks are spaced apart for a portion above the reversely bent extremities so that a part connected by this double safety hook structure is first inserted between the hooks and then turned more than 90° relatively to the double hooks, lowered below the reversely turned extremities forming the hooks, and rotated reversely below the extremities of the hooks and to make a double engagement of the part which is connected, and to prevent an accidental reversing and disengaging movement.
